UNITED STATES PATENT OFFICE

GEORGE W. PRATT, OF OAKLAND, CALIFORNIA

HANDCUFF

Application filed November 11, 1929. Serial No. 406,337.

This invention is for an improvement in handcuffs, and is particularly directed to a pair of handcuffs having a rigid spacer bar or stock, one of the cuffs being collapsible and foldable within shield members which form a handle for use of the other cuff as a nipper.

The main object of the invention is to provide a pair of handcuffs which may readily be converted into a nipper.

Another object of the invention is to provide a pair of individually adjustable cuffs having a rigid spacer bar or stock and comprising a nipper cuff and a retractile cuff, the nipper cuff being positively locked by the retractile cuff, except when said retractile cuff is fully retracted.

Other objects and advantages of the invention will become apparent as the following description is read on the drawings forming a part of this specification.

The invention consists primarily of a rigid stock having formed integrally, at one end, outwardly extending shields forming a handle, and at the other end, a bifurcated cuff member, to which is pivotally connected a complementary cuff member provided with teeth on the periphery opposite the pivotal connection. A spring actuated plunger 30 pawl is slidably mounted in a counterbore in the stock and engages the teeth on the complementary cuff member. A rod, integral with the pawl extends through a bore through the stock and cooperates with the periphery of cooperating ears on the retractile cuff, which are provided with radially disposed semi-cylindrical recesses on the cooperating faces adapted to register and form a cylindrical aperture for reception of the end of the rod when the cuff is retracted, the retractile cuff comprising a quadral element pivotally mounted within the shields and having cooperating locking members on the sections opposite the connection pivot, two sections being pivoted together at each side of the pivotal connection, each pair being foldable within a shield.

The invention is adequately illustrated in the accompanying drawings in which:

Fig. 1 is a section taken on line 1—1 of Fig. 2;

Fig. 2 is a section taken on line 2—2 of Fig. 1, except three members of the retractile cuff which are shown in full line;

Fig. 3 is a detail view of the retractile cuff locking mechanism;

Fig. 4 is a fragmentary sectional view to indicate the relation of the retractile cuff to the pawl plunger rod;

Fig. 5 is a side elevation of the invention, showing the retractile cuff folded within the shields;

Fig. 6 is a view of the cooperating unlocking recesses in registry adapted to receive the end of the pawl plunger rod.

Similar reference characters are used to designate similar parts throughout the several views.

The stock consists of a cylindrical portion 10 terminating at one end in a pair of oppositely extending shields 29 and 30 which form a nipper handle 33, the opposite end continuing into an enlarged portion 53 from one side of which extends an integral bifurcated arcuate cuff member 25, to the end of which is pivotally connected a complementary cuff member 22, forming a nipper cuff. The enlarged portion 53 has a slot 54 formed therein to receive the ratchet section 26 of cuff member 22. An elongated slot 27 is formed in the cylindrical section 10 in registry with a central longitudinal bore 11 extending through the stock, and which terminates in stepped counterbores 12, 19.

The complementary cuff member 22 is pivotally connected to member 25 as indicated at 24, and has an integral ratchet 26, the periphery of which is formed to a radius with pivot 24 as a center, and has ratchet teeth 21 formed in the periphery opposed to opening movement of the cuff member 22.

A plunger pawl 18 is slidably mounted in the counterbore 19 and is urged into cooperative relation to ratchet 26 by means of a spring 13 housed in counterbore 12, and is provided with complementary teeth 20 adapted to cooperate with teeth 21 in ratchet 26. Integral with, or fixed to pawl 18 is a plunger 52 extending through the bore 11 and

having a pin 28 transversely secured therein and extending outwardly through slot 27 forming a finger release for pawl 18.

The retractile cuff 31 comprises a quadral

- 5 element consisting of two main arcuate cuff members 34 and 35 pivotally connected together at one end, and to the stock through the side walls of the shield 33 in registry with plunger 52, these members having complementary ears of cylindrical form provided with semi-cylindrical recesses 41 and 42 radially disposed in the cooperating faces, which are adapted to register when these members are folded within the shields 29 and 30 and receive the end of plunger 52. Pivotally secured to the opposite end of member 34 as at 38 is an arcuately formed ratchet member 36 provided with standard gear teeth 50 formed in the periphery of an extension 49 which is formed to a radius with pivot 40 as a center when the cuff is closed.

Pivotally secured to the opposite end of member 35 as at 39 is an arcuately formed locking member 37 having an enlargement 43 in which is formed a housing 44 through which ratchet 49 is adapted to pass and in which a toothed wheel 45 is rotatably mounted on a pin 46.

A spring actuated pawl 47 is pivoted with 30 in the housing 48 in such manner as to prevent rotation of wheel 45 when an attempt is made to withdraw ratchet 49, but permitting rotation of the wheel when the ratchet 49 is forced inwardly to closing position. A key hole 51 permits the use of a key for moving pawl 47 out of engagement with wheel 45, whereby the cuff may be opened.

The operation of the cuff is as follows:

With both cuffs in closed position as indicated in Fig. 2, pawl 18 cannot be moved out of engagement with ratchet 26, as the plunger 52 is prevented from moving upwardly by the ears on members 34 and 35. By lifting pawl 47 by means of a key operating through key-hole 51, ratchet member 49 may be withdrawn from housing 44 and the cuff folded within shields 29 and 30 as indicated by dotted lines in Fig. 2. In this position, the recesses 41 and 42 are in registry, forming a cylindrical aperture as shown in Fig. 6, which aperture is in registry with the end of plunger 52, which may then be drawn upwardly by means of pin 28, releasing pawl 18 from engagement with ratchet 26 and permitting withdrawal of ratchet 26 from the slot 54.

Having described an operative method of constructing and operating the invention, it 65 will be understood that variations in construction and arrangement of parts which are consistent with the appended claims may be resorted to without detracting from the spirit or scope of the invention, or sacrificing any of the advantages thereof.

I claim:

1. A pair of handcuffs comprising a centrally bored stock having a cuff secured to each of its respective ends, one cuff comprising a quadral element, two of the sections thereof being pivotally related to each other by an overlapped joint and to the stock, the inner face of the respective overlaps having radial grooves therein for registration with the bore, a spring actuated rod within the bore for entering the grooves when in registration with the bore, a toothed dog carried by the opposite end of the rod, the other of the cuffs being composed of a bifurcated arcuate section and a complementary arcuate section pivotally related to the first named section, the last named section being provided with teeth on the outer peripheral face thereof for engagement with the dog. 75

2. A pair of handcuffs comprising a centrally bored stock having a cuff secured to each of its respective ends, two of the sections of one cuff being pivotally related to each other by an overlapped joint and to the stock, the inner face of the respective overlaps having radial grooves therein for registration with the bore, a spring actuated rod within the bore for entering the grooves when in registration with the bore, a toothed dog carried by the opposite end of the rod, the other of the cuffs being composed of a bifurcated arcuate section and a complementary arcuate section pivotally related to the first named section, the last named section being provided with teeth on the outer peripheral face thereof for engagement with the dog. 80

3. A pair of handcuffs comprising a centrally bored stock having a longitudinal slot in the wall thereof and communicating with the bore, one of the cuffs being composed of a plurality of pivotally connected sections, two of the sections being pivotally related to each other and to the stock by an overlapped joint, the inner face of the overlap having semicircular radial grooves therein for registration with each other and the bore, a spring actuated rod within the bore for cooperation with the grooves, a stud carried by the rod and extending through the slot, said bore terminating in a housing at one of its ends, a toothed dog supported within the housing, a cuff composed of a bifurcated arcuate member carried by the last named end of the stock, an arcuate member pivotally related to the bifurcated member, said arcuate member having teeth on its outer peripheral edge for engagement with the teeth of the dog and means for disengaging the teeth of the dog with the teeth of the arcuate member. 105

4. A pair of handcuffs comprising a rigid stock, a retractile cuff pivotally jointed thereto, a spring operated plunger pawl and a plunger extending through said stock, the 110

end of said plunger being adapted to co-operate with complementary recesses formed in the contacting faces of the pivotal joint of said retractile cuff when said cuff is folded down within a shield.

5. A pair of handcuffs consisting of a nipp-
per cuff, a retractile cuff having a pivotal
joint, a rigid stock having a central bore and
a counterbore, a spring actuated plunger pawl
having an integral rod extending through
said bore, said retractile cuff having semi-
cylindrical recesses radially formed in the
contacting faces of the pivotal joint thereof
and so disposed as to be in registry forming a
cylindrical aperture registering with said rod
when said cuff is in full retracted position.

6. In combination a pair of handcuffs, a
rigid stock having an axial aperture and a rod
extending through said aperture, a shield
formed at one end of said stock, one of said
cuffs having a common pivotal connection
within said shield; complementary semi-cy-
lindrical recesses formed in the contacting
faces of said connection and radially dis-
posed, and adapted to register to form a
cylindrical aperture in registry with said rod
when said cuff is retracted within said shield.

7. A pair of handcuffs consisting of a nipp-
per cuff, a retractile cuff and a shield there-
for, a rigid stock and a plunger extending
axially therethrough said retractile cuff hav-
ing a unitary pivotal connection to said stock
within said shield, said connection having
complementary radial recesses adapted to
35 form a cylindrical aperture in registry with
said plunger when said cuff is retracted with-
in said shield.

In testimony whereof I have affixed my
signature.

GEORGE W. PRATT.
